QUICK ACTING VALVE

William H. Lannert, Skokie, Ill., assignor, by mesne assignments, to FMC Corporation, a corporation of Delaware

Filed May 24, 1957, Ser. No. 661,394
6 Claims. (Cl. 137—625.27)

This invention relates to a quick acting valve for rapidly flexing diffuser tubes in an air diffuser installation of the type used to aerate sewage contained in a tank, to dislodge solids accumulated on the surface of the diffuser tubes without removing the diffuser tubes from the sewage in which they are immersed.

The valve comprising the present invention is capable of use in any air diffuser installation in which the diffuser tubes have a flexible porous wall, regardless of whether the diffuser unit is of the fixed or swing type. For the sake of clarity the valve will be described in connection with a swing diffuser of the type shown in my prior Patent No. 2,328,655, issued September 7, 1943. The diffuser tubes are preferably made, at least in part, of flexible porous fabric, such as "Saran" cloth, but it is possible to use any diffuser tubes which are provided with a collapsible, foraminated fabric through the interstices of which air or gas passes in fine bubbles into the liquid in which the diffuser tubes are immersed. The proper diffusion of air into the sewage tank depends upon the porosity of the diffuser tubes, and, in time, the pores of the diffuser tubes become clogged with solid matter which normally accumulates on the outer wall surface of the diffuser tubes.

It has been found that the solid matter accumulated on the surfaces of the diffuser tubes may be dislodged by the rapid flexing of the porous fabric of the diffuser tubes. The efficiency of this method of cleaning diffuser tubes while they are immersed in sewage depends largely upon the speed with which they may be deflated and reinflated. The deflation and reinflation of the tubes is controlled by the operation of the valve.

In accordance with the present invention, the valve is adapted to be moved quickly between open and closed positions. In the open position of the valve, the opening to the atmosphere is closed, and air under pressure flows from an air main through the valve housing, and then to the pipes which carry it to the diffuser tubes. In the closed position of the valve, the air from the air main cannot pass through the valve housing, and the opening to the atmosphere is open. The pressure of the sewage forces the air in the diffuser tubes back through the pipes and through the valve housing into the atmosphere. The efficiency of the valve in flexing the diffuser tubes depends upon its speed of reversal and the positiveness of its action in each direction.

The valve constructed in accordance with the present invention permits the diffuser tubes to be completely deflated and completely reinflated between successive strokes with great rapidity, and the alternate deflation and reinflation may be repeated until all of the solid matter accumulated on the surface of the diffuser tubes is dislodged therefrom, thereby obviating the necessity of removing the diffuser tubes from the sewage tank for cleaning.

In the drawings a valve embodying the invention is positioned in a stationary header which is connected to an air main. The air flow controlled by the valve passes through an elbow and a pair of pipes to a plurality of diffuser tubes mounted on the lower end of the lowermost pipe.

The valve stem passes through an aperture in a flange extending outwardly from the valve housing. The aper-

2

ture has sufficient clearance to permit the stem to slide easily in either direction and has a nut threaded on each side of the flange. One nut may be tightened against one surface of the flange to prevent movement of the valve stem in one direction, and the other nut may be tightened against the opposite surface of the flange to prevent movement of the valve stem in the opposite direction. Thus the valve may be locked in open position to permit normal flow of air from the air main to the diffuser tubes, or may be locked in closed position to permit repair or replacement of any portion of the diffuser system. The nuts may be spaced apart a predetermined distance on the stem to permit a limited movement of the stem in either direction. The nuts are positioned to cause the valve to be seated in its closed position at one end of said movement, and in its open position at the other end of said movement. This limited movement is along a straight line, and the valve may be moved very quickly between its open and closed positions.

The structure by means of which the above and other advantages are attained will be described in detail in the following specification, taken in conjunction with the accompanying drawings, showing a preferred illustrative embodiment of the invention, in which:

FIGURE 1 is a fragmentary sectional view of a sewage tank with a swing diffuser installation shown in elevation in its operative position within the tank;

FIG. 2 is a cross sectional view, taken along the line 2—2 of FIG. 1;

FIG. 3 is a cross sectional view of the valve locked in open position, showing a portion of the elbow and upper pipe in elevation;

FIG. 4 is a view similar to FIG. 3, with the nuts on the valve stem arranged to permit movement of the valve in either direction; the valve being shown in open position, and the closed position of the valve being indicated in dotted lines;

FIG. 5 is a view, partly in section and partly in elevation, showing the valve locked in closed position; and

FIG. 6 is a cross sectional view of a modified embodiment of the invention in which the valve assembly comprises two valves disposed angularly to each other.

In the drawings, the reference numeral 2 indicates a sewage tank having a vertical wall 3 offset angularly adjacent its upper edge, as indicated at 4, to provide space for an air main 5 adapted to serve tanks on opposite sides of wall 3. The angularly offset section 4 of the wall terminates in a vertical section 6 in which a tubular L-shaped joint 7 is embedded. A tubular conduit 8 communicating with air main 5 through a neck 9 has one end connected with the open end of the horizontal portion of the L-shaped joint 7. The vertical portion of joint 7 terminates in an open end flush with the top surface of wall section 6 and has a horizontal flange 10 secured to an annular flange 11 at the lower open end of a stationary header 12.

The stationary header 12 extends above the upper edge of wall section 6 and serves as a housing for a valve 13 adapted to control the flow of air from the main 5. The lower portion of valve housing extending upwardly above the inner edge of flange 11 is cylindrical, as indicated at 14, and is provided with an annular shoulder 15 extending inwardly from the inner surface of the cylindrical portion of the housing. An annular ring valve seat 16 is positioned on the upper edge of the annular shoulder 15 to engage the lower surface of valve 13, as hereinafter described, when the valve is in closed position.

The portion of valve housing 12 above the ring valve seat 16 is substantially a continuation of the lower portion except that one portion of the cylindrical wall is cut out to form a part of a circular vertical opening 17. The cylindrical wall 14 terminates in a horizontal wall 18

having an annular opening 19 concentric with the lower open end of the valve housing. The portion of cylindrical wall 14 contiguous to the opening 17 is provided with a flange 20. This flange extends around the lower portion of the circular opening 17 and its ends terminate in the horizontal plane of wall 18. The portion of the circular opening 17 above the plane of wall 18 is defined by a wall 21 shaped like a sector of the frustum of a cone. The wall 21 is provided with an integral flange 22 having its outer edge coplanar with the outer edge of flange 20. The ends of flanges 20 and 22 abut each other to form a complete circle surrounding the opening 17.

The wall 21 has a radial strip 23 depending vertically therefrom in spaced relationship to the vertical plane of the flange 22. An integral cylindrical boss 24 extends horizontally from the lower end portion of strip 23 and its outer end is flush with the outer edges of flanges 20 and 22. The boss 24 is provided with a threaded horizontal bore 25 adapted to receive a threaded end 26 of a stud 27. The bore 25 is concentric with the circular opening 17.

An elbow 28 has a vertically disposed circular opening 29 of the same size as opening 17 and provided with a flange 30 extending completely around the opening. The outer edge of flange 30 is parallel to flanges 20 and 22. An annular sealing ring 30 is interposed between the meeting faces of the valve housing 12 and the elbow 28 adjacent the vertically disposed circular openings 17 and 29. The seal prevents leakage of air through the joint so that the air from the air main 5 flows through the valve housing 12, when valve 13 is open, and into the elbow 28. An upper pipe 31 secured to the other open end of elbow 28 is pivotally connected to a lower pipe 32 by a knee joint 33, and a header 34 connected to the opposite end of pipe 32 directs the air into a plurality of diffuser tubes 35 connected to the header. A bumper rod 36 is mounted on the underside of the header 34 to protect the diffuser tubes from bumping into the wall 3.

The elbow 28 is provided with a horizontal boss 37 disposed centrally of the opening 29 and having its outer end flush with the outer edge of flange 30. The boss 37 is provided with a bore 38 aligned with bore 25. A pair of bearing sleeves 39 mounted in the bore 38 facilitate pivotal movement of the elbow 28 about the stud 27. The outer end of the bore 38 is counterbored as indicated at 40, to form a recess in which a compression spring 41 is seated. The outer end of stud 27 is threaded, as indicated at 42. A washer 43 positioned on the stud 27 is held against the spring 41 by means of a nut 44 threaded on the end of stud 27. The nut 44 is tightened to compress the spring as much as possible, and is then slackened off about an eighth of a turn to cause the spring to hold the elbow against the sealing ring firmly enough to prevent leakage of air and yet have sufficient resilience to permit the elbow to be moved pivotally relative to the valve housing. After the nut 44 is positioned, a second nut 45 is threaded on the stud 27 to lock the nut 44 in the desired position.

A flange 46 extends outwardly from the lower end of wall 21 and is provided with a circular opening 47 concentric with the opening 19 in horizontal wall 18. The valve 13 comprises a valve disk 48 dished upwardly around its outer edge, as indicated at 49, to form tight seal with the valve ring seat 16 when the valve is in its closed position. A sealing ring 50 is secured to the lower surface of a second valve disk 51 positioned concentrically above the valve disk 48. An annular sealing ring 52 on top of the disk 51 is adapted to engage the underside of a collar 53 when the valve is in its open or uppermost position to form an airtight seal around the opening 19 in which the collar 53 is fitted.

A valve stem 54 threaded into an aperture in disk 48, as indicated at 55, projects upwardly through the sealing ring 50 and openings 19 and 47. The stem 54 is thread-

ed throughout its length, and its outer diameter is slightly smaller than the diameter of opening 47 to permit it to slide therethrough freely. A spring 56 encircling the valve stem floats on top of the disk 51. The parallel relationship between the flange 46 and the two annular valve seats 16 and 52, and the concentric relationship of the openings 19, 47 and the opening circumscribed by the annular shoulder 15 facilitate locking the valve in either open or closed position or in position in which the valve may be moved rapidly between said open and closed positions. A nut 58 is threaded on stem 54 between flange 46 and the spring 56. Another nut 59 is threaded on stem 54 above the flange 46 and is locked against separation by a lock washer 60 secured to the top end portion of the valve stem 54.

The operation of the valve will now be described. In FIG. 3 the valve is shown in its normal operating position. The valve is locked in its open position so that air from main 5 can flow through the housing 12 and into elbow 28. Its flow path from the elbow has been previously described. The sealing rings 50 and 52 cooperate to prevent any air from flowing through the opening 19. The ring 50 prevents leakage of air around the edges of the aperture in the center of the valve disk 51 through which the stem 54 extends, and the ring 52 prevents any leakage between the outer edge of the disk 51 and the bottom of the collar 53.

The nut 59 may be tightened against the top of the flange 46 to lock the valve in any open position. The flow of air through the valve housing 12 to the elbow 28 is continuous when the valve is locked in any open position, but the amount of the air flowing through the valve may be reduced or increased by changing the position in which the valve is locked. Since the sealing ring 50 is secured to the disk 51 the stem 54 may be moved downwardly to position the valve disk 48 closer to the valve seat 16 without breaking the air seal around the opening 19.

When the diffuser tubes 35 are to be flexed, the nuts 58 and 59 are rotated to the solid line positions shown in FIG. 4. The valve stem 54 is moved downwardly by pressure against its upper end. This pressure may be applied by means of a handle (not shown) or by any other suitable means. The valve disk 48 is moved downwardly to seat on the ring 16 to stop the flow of air from the main 5. Just before the disk 48 is seated on the ring 16 the nut 58, which is smaller than the aperture 19, strikes the spring 56 to kick the valve disk 51 away from the bottom of the collar 53 to break the seal around the opening 19. The pressure of the sewage is greater than atmospheric pressure and collapses the diffuser tubes quickly, forcing the air from the diffuser tubes and pipes 31 and 32 through the opening 19 into the atmosphere.

As soon as the diffuser tubes 35 are collapsed, the valve stem 54 is pulled up to seat the disk 51 and ring 52 against the bottom of collar 53, thereby causing the air from the main 5 to flow into the diffuser tubes to reinflate them. After the diffuser tubes have been deflated and reinflated a few times the solid matter is dislodged from the tubes and the valve is again locked in the open position shown in FIG. 3.

If the diffuser tubes have to be lifted from the sewage for repair or replacement, the nut 58 is rotated to the position shown in FIG. 5 to lock the valve inclosed position to prevent escape of air from the main 5 while the necessary repairs or replacements are being made.

In the embodiment of FIG. 6, the valve housing 61 is similar to the housing 12 and the same reference numerals will indicate identical structure. The detailed description of such identical structure will not be repeated. The flow of air through the system is essentially the same in both embodiments.

The horizontal wall 62 of the housing 61 is provided with an opening 63 through which the valve stem 64 extends. A sealing ring 65 seated within the opening 63 fits

snugly around the valve stem 64 to provide an airtight seal. The valve housing 61 is provided on one side with a vent opening 66 adapted to be covered or uncovered by a valve disk 67 pivotally mounted adjacent the opening 66, as indicated at 68.

The valve disk 67 is provided with a tail piece 69 adapted to be engaged by a collar 70 or 71, depending on the direction of movement of the valve stem 64, to move the valve disk 67 so as to uncover or to cover the vent opening 66. The collars 70 and 71 are keyed to the valve stem 64 in spaced relationship. The valve 48 is mounted on the lower end of the valve stem 64, and the downward movement of the valve stem which seats the valve disk 48 in closed position causes the collar 70 to engage the upper surface of the tail piece 69 to move the valve disk 67 away from the vent opening 66 just before the valve disk 48 is moved into sealing engagement with valve seat 16.

When the valve stem 64 is pulled up to lift the valve disk 48 off its seat, the collar 71 engages the underside of the tail piece 69 and moves the valve disk 67 into sealing engagement with the vent opening 66. The valve disk 67 and its tail piece 69 are so dimensioned that the free end of the tail piece is always positioned between the collars 70 and 71. The collar 70 abuts the underside of the horizontal wall 62 to limit the upward movement of the drive stem 64 when the valve disk 67 is in closed position against the vent opening 66. The sealing engagement of the valve disk 48 with the ring valve seat 16 limits the downward movement of the valve stem 64 and prevents the collar 70 from moving downwardly past the end of the tail piece 69.

While I have described two preferred embodiments of my invention in considerable detail, it will be understood that the description is intended to be illustrative, rather than restrictive, as many details may be modified or changed without departing from the spirit or scope of my invention. Accordingly, I do not desire to be restricted to the exact details of construction described.

I claim:

1. A valve comprising a valve housing having a first opening adapted to be connected to a main, a second opening adapted to be connected to a pipe, and a third opening communicating with the atmosphere, a valve seat adjacent said first opening, an annular valve seat adjacent said third opening, said annular valve seat being spaced from and parallel to said first valve seat, a valve disk positioned between said valve seats, a valve stem secured to said valve disk and projecting through the opening of said annular valve seat, said valve disk being movable between said seats to close or open the opening adjacent thereto, guide means engageable with said stem to guide the movement of said valve disk, said guide means comprising the sole means for restricting the lateral movement of said valve disk, and stop means adjustably mounted on said stem to engage opposite sides of said guide means and thereby limit the movement of said valve disk in each direction.

2. A valve comprising a valve housing having a first opening adapted to be connected to a main, a second opening adapted to be connected to a pipe, a third opening communicating with the atmosphere, two parallel spaced annular valve seats adjacent two of said openings and a flange extending parallel to the planes of said valve seats, said flange having an aperture, a pair of valve disks operable to move between said seats to close or open the openings adjacent thereto, a valve stem having one end secured to one of said valve disks, said valve stem projecting through said other valve disk, one of said annular valve seats and the aperture of said flange, said flange comprising the sole means for restricting the lateral movement of said valve stem, and adjustable stop means on said stem on opposite sides of said flange engageable with said flange to limit the movement of said valve disks in each direction.

3. A valve comprising a valve housing having a first

opening adapted to be connected to a main, a second opening adapted to be connected to a pipe, a third opening communicating with the atmosphere, two parallel spaced annular valve seats and a flange extending parallel to the planes of said valve seats, said flange and said valve seats having concentric openings, a pair of valve disks positioned between said seats, said valve disks being each engageable with one of said valve seats to direct air in different paths through said housing, a valve stem secured to one of said valve disks, said stem projecting through openings in said other valve disk, in one of said valve seats, and in said flange, a coiled spring encircling said stem between said second mentioned valve disk and said flange, a nut engaging said stem on one side of said flange, said nut being engageable with said coiled spring to compress it and thereby force said second mentioned valve disk out of sealing engagement with its seat, and a second nut engaging said stem on the opposite side of said flange, said nuts being adjustable to engage opposite sides of said flange in any position of said first mentioned valve and thereby lock said first mentioned valve disk in predetermined position.

4. A valve comprising a valve housing having a first opening adapted to be connected to a main, a second opening adapted to be connected to a pipe, a third opening communicating with the atmosphere, two parallel spaced annular valve seats and a flange extending parallel to the planes of said valve seats, said flange and said valve seats having concentric openings, a pair of valve disks positioned between said seats, said valve disks being movable between said valve seats, said valve disks being each engageable with one of said valve seats to close or open the opening adjacent thereto and thereby direct air in different paths through said housing, a threaded valve stem secured to one of said valve disks, said stem projecting through openings in said other valve disk, one of said valve seats, and in said flange, a nut threaded on said stem between said one valve seat and said flange, said nut being movable into position relative to said flange to limit movement of said first mentioned valve disk in one direction, and a second nut threaded on said stem on the opposite side of said flange, said second nut being movable into position relative to said flange to limit movement of said first mentioned valve disk toward said other valve seat.

5. A valve comprising a valve housing having a first opening adapted to be connected to a main, a second opening adapted to be connected to a pipe, a third opening communicating with the atmosphere, two parallel spaced annular valve seats and a flange extending parallel to the planes of said valve seats, said flange and said valve seats having concentric openings, a pair of valve disks positioned between said seats, said valve disk being movable between said valve seats, said valve disks being each engageable with one of said valve seats to close or open the opening adjacent thereto and thereby direct air in different paths through said housing, a stem secured to one of said valve disks, said stem projecting through openings in said other valve disk, in said flange, and in one of said valve seat, and means engageable with said stem, said means comprising two members adapted to be held in engagement with said flange to lock said first mentioned valve disk against movement in any predetermined position, and movable out of engagement with said flange to permit the stem and one of said members to cooperate to effect movement of said first mentioned valve disk in either direction.

6. A valve comprising a housing having a first opening adapted to be connected to a main, a second opening adapted to be connected to a pipe, and a third opening communicating with the atmosphere, a valve seat in said housing, a flange on said housing extending parallel to the plane of said valve seat, said flange having an aperture aligned with said valve seat, a valve disk movable into and out of sealing engagement with said valve seat to close or open said first opening, a threaded valve stem secured

to said valve disk and extending through said aperture, said valve stem being slidable within said aperture, adjustable stop means threaded on said stem on opposite sides of said flange and movable on said stem so as to engage said flange in any predetermined position of said valve disk to limit the movement of said valve disk, a second valve seat in said housing, and a second valve disk adapted to be seated on said second valve seat to close said third opening, the stop means on said valve stem on the side of said flange closest to said second valve seat being operable to move said second valve disk out of sealing engagement with said second valve seat at any predetermined point of the movement of said first mentioned valve disk toward its sealing engagement with said first mentioned valve seat.
